UNITED STATES PATENT OFFICE.

MAGDA ERNESTINE ELISE PAETZOLD, OF HAMBURG, GERMANY, ASSIGNOR TO
ADOLPHUS LENERT WEX, OF HAMBURG, GERMANY.

SNAP-BUTTON.

1,031,022.

Specification of Letters Patent.

Patented July 2, 1912.

Application filed March 18, 1911. Serial No. 615,224.

To all whom it may concern:

Be it known that I, MAGDA ERNESTINE ELISE PAETZOLD, a subject of the German Emperor, and resident of No. 21/23 Kolonaden, Hamburg, Germany, have invented 5 certain new and useful Improvements in Snap-Buttons, of which the following is a specification.

This invention relates to snap buttons for 10 articles of dress, gloves, bags, purses and the like and has for object improvements therein, whereby an exceptionally simple and inexpensive snap button is realized having the advantage of holding the pieces to 15 be attached directly one on top of the other with the button invisible.

The invention consists in an improved 20 snap button in which one member is a plate having an upwardly dished edge tapering to nothing at the rear side of the plate, and the other member, engaging with the first by the usual knob device, is covered by the said 25 first member, the dished edge of which fits closely around the periphery of the second member and provides a secure hold.

The holes by means of which the buttons 30 are sewn on to the material of the articles to be fastened are situated close to the rim of the dished edge of the button, so that the material lies closely around the dished edge.

With this improved arrangement on engagement of the two members the pieces to be attached lie directly one on top of the other and the button is invisible, while the 35 dished edge on the front of the one button member resists any pull exerted on the other member, so that a securer hold is obtained and springing loose of the button prevented.

Two constructions of the improved snap 40 button are illustrated by way of example in the accompanying drawings, which are considerably more than full size.

Figures 1 to 3 illustrate a lozenge shaped button in inverted plan, sectional view 45 through A—B, and sectional view through C—D of Fig. 1 respectively. Fig. 4 shows a round snap button.

One member of the improved snap button consists of a plate or flat base *a* carrying the 50 locking stud or knob *b*, and with its rear part *a'* bent slightly downward (see Fig. 3).

The plate *a* has on front an upwardly dished edge which gradually tapers away to nothing toward the rear part *a'*. The other member *e* has a flat upper face a cup or 55 socket *f* and springs *g* which project into the cup as shown, so as to retain the knob *b* when the button is fastened. Holes *d* are provided in both members, close to the edge, for the purpose of sewing the members to 60 the material. Additional perforations are formed in the front portion of the rim in proximity to the upper edge thereof.

In use, one member *a* is attached to one part *h* of, say, an article of dress, by means 65 of thread *i* passing through the holes *d*, the cloth *h* which is folded over in front, lying over the edge *c* and covering therefore the member *a* of the button. The other member *e* is attached to the other similarly folded 70 part *k* of the article of dress. When the button is being fastened the member *a* fits closely over the member *e*, the fastened snap button being invisible.

What I claim is:—

A snap button comprising a flat base having a stud and an upturned rim which is perforated at its front portion in proximity to its upper edge, said base and rim-edge gradually approaching each other from said 80 front portion toward the rear of the base and the rear edge of the base lying in the same plane as the edge of the upturned rim, the base being adapted to be overlaid by one section of the garment, while part of 85 said section is drawn against the outer side of the upturned perforated rim portion when sewn thereto, and a socketed member having a flat upper face adapted to be bodily received by the base within its rim to engage the stud, said socketed member being adapted to be secured to the other garment section, whereby the base and the socketed member are concealed when the button is 90 closed.

Signed by me at Hamburg, Germany this 95 8th day of March 1911.

MAGDA ERNESTINE ELISE PAETZOLD.
